UNITED STATES PATENT OFFICE.

CARL RASMUSSEN, OF BRUNSWICK, GERMANY.

CALCULATING-MACHINE.

1,199,607.

Specification of Letters Patent. Patented Sept. 26, 1916.

Application filed November 25, 1914. Serial No. 874,011.

To all whom it may concern:

Be it known that I, CARL RASMUSSEN, engineer, subject of the King of Norway, residing at Brunswick, Germany, have invented certain new and useful Improvements in Calculating-Machines, of which the following is a specification.

My invention relates to improvements in setting disks, such as are used for example 10 in calculating machines for setting the values to be transmitted to the registering mechanism.

My invention relates more particularly to setting disks of that class in which each 15 of the disks is provided with shiftable teeth representing the values to be transmitted to the registering mechanism, the desired number of the said teeth being adapted to be shifted into operative positions by means 20 of cam disks.

The object of the improvements is to provide novel means for shifting the desired number of teeth into or out of operative positions.

25 For the purpose of explaining the invention I shall refer to a calculating machine which has been shown and described in detail in the United States Patent No. 1,100,689; and I wish it to be understood, 30 that my invention is not limited to the construction of the machine shown in the accompanying drawing and that it may also be embodied in machines other than calculating machines.

35 In the drawing—Fig. 1, is a cross-section of the machine, Fig. 2, is a partial plan view thereof with the cover of the casing removed, and Figs. 3 to 5 are detail views of operating parts of the machine.

40 The same letters of reference have been used in all the views to indicate corresponding parts.

Referring to the embodiment of the invention illustrated in the drawing, a shaft y 45 mounted in the side walls of the machine casing has the setting disks r secured thereto each disk being provided with nine radially shiftable teeth x . When the setting disks are rotated, the teeth x which have 50 been previously shifted into operative positions engage the intermediate gear wheels z which latter are in mesh with gear wheels s , so that the number set upon the setting disks r is 55 transmitted to the numeral wheels by the rotation of the disks r . A rocking lever

t is loosely mounted on the shaft y at one side of each of the disks r and projects through a slit g made in the cover p of the machine casing. The lever t is connected 60 with an arm o which takes part in the rocking movement of the lever t . Each of the teeth x is formed with a laterally projecting pin x^1 adapted to be engaged by the pawl n , which is arranged for such engagement and is pivoted to the arm o , as shown at n^2 . The pawl n which is formed with an inclined cam groove n^1 , is adapted to be rocked toward and away from the setting disk r , as is shown in Figs. 4 and 5. When 70 the said pawl is rocked away from the setting disk and in the position shown in Fig. 2, it moves along the teeth x without affecting the same when the lever t is rocked, and when it has been rocked toward the setting 75 disk it engages the pins x^1 when the lever t is being rocked to shift the said teeth x either outward into operative positions or inward into inoperative positions. Normally the pawl is out of position for engagement with the pins x^1 and is held in this position by a spring m . For placing the pawl in position for engagement with the pin x^1 , a cam disk l is provided and has on a portion of its circumference a cam 80 face l^1 the disk l being rocked only for setting and resetting the teeth x . As appears from Fig. 1, the open part of the cam face l^1 extends over the part of the circumference of the disk l which corresponds to the 85 teeth x . Therefore the setting disk r and the teeth x can be rotated by means of the machine crank k , without the teeth x engaging the pawl n , but when the disk l is turned in the direction of the arrow l^2 , 90 shown in Fig. 1, the cam face l^1 engages the pawl n and rocks the same toward the setting disk r . If now the hand lever t is turned, the cam groove n^1 of the pawl n 95 shifts the radial teeth outward or inward. If, thereafter, the cam disk l is turned backward and in the direction of the arrow l^3 shown in Fig. 1, the cam face l^1 releases the pawl n , so that the latter is retracted away from the disk r by its spring m . Now the disk r 105 and its projecting or retracted teeth can be freely rotated, so that the value set thereon is transmitted to the numeral wheel s .

In the embodiment shown in the drawing, the following mechanism is provided for 110 turning the cam disk l . On the machine frame a , a shaft f is mounted which is pro-

vided at its left hand side with a hand lever j^2 for rotating the same (see Fig. 3), and the said shaft carries arms i one for each of the setting levers, the free ends of the 5 said arms being connected with the cam disks l through links h . By turning the shaft j in the direction of the arrow j^1 shown in Fig. 1 the cam disks l are also rotated, as is indicated in Fig. 1 by the position 10 of the arm i and the link h shown in dotted lines. The shaft j is common to all the cam disks l , and the connection can either be such, that each of the links is connected with the shaft by an arm i of its own, 15 or such that all the links h are in engagement with a rod b which is parallel to the shaft j and rocks about the same, as is shown in Fig. 1.

Each of the setting levers t is locked in 20 its set positions by means of a toothed sector t^2 connected therewith and a spring actuated pawl f engaging in the teeth of the sector. t^1

If after turning the cam disks l and setting a value the machine crank k were turned, before the cam disks l are returned into their normal positions shown in Fig. 1, the pins x^1 of the teeth x would be engaged by the pawls provided with the cam slots, 30 so that according to the direction of the rotation of the machine crank the teeth x , which have been set in operative positions are retracted into inoperative positions or the teeth which are in inoperative positions 35 are set in operative positions. To avoid this and to assure the proper operation of the machine, interlocking mechanism is provided between the crank k and the shaft j which turns the cam disks, and which interlocking mechanism is adapted to lock the 40 crank as long as the cam disks have been turned out of their normal positions. The interlocking mechanism is preferably constructed in such a manner as to lock cam 45 disks l , as long as the crank is out of its normal position. Finally a third locking mechanism may be combined with the interlocking mechanism, by means of which the 50 crank and the setting levers t are made to be dependent on each other. To show what may be done, the drawing shows an example of such a construction.

Through the intermediary of gear wheels k^1 , k^2 , and k^3 a locking disk g is connected 55 with the machine crank k , and a lateral notch g^1 of the said locking disk is engaged by a nose e^1 of a slide e . In the normal position of the cam disks l shown, in Fig. 2, the said slide is located opposite a notch 60 d^1 of a disk d secured to the driving shaft j of the cam disks. When rotating the shaft j for the purpose of turning the cam disks l and in the direction of the arrow j^1 shown in Fig. 1, the margin of the disk d is shifted 65 in front of the slide e so as to lock the same.

Thereby the machine crank is also locked, for the reason that the slide e locks the disk g which is connected therewith. Therefore, for releasing the crank the cam disks l must always be rocked into initial positions. On 70 the other hand, when the crank is being rotated, the disk g forces the slide e into the notch of the disk d , so that the shaft j and the cam disks l are locked to the end of the rotation of the crank. 75

The slide e has the further function to interlock the setting levers t and the crank k . For this purpose it is provided with notches e^2 and opposite to the said notches arms j^1 are located which are connected with the locking pawls f . When upon rotation of the machine crank k the slide e is shifted by means of the disk g in the direction of the arrow shown in Fig. 2, instead of the notches e^2 the margin of the slide engages at the 85 rear of the levers j^1 , so that the pawls f , and thereby the levers t are locked. On the other hand, when either one of the levers t is not exactly in its setting position, the 90 crank is locked, because in this case the corresponding pawl f which bears on a tooth of the sector t^2 rocks its arms j^1 into the notch e^2 of the slide e and thereby locks the slide and crank in the inoperative positions. 95

The slide e is pulled by a spring e^3 into the inoperative position shown in Fig. 2. For pressing the pawls f in contact with the sectors t^2 springs c are provided.

I claim herein as my invention:

1. In an apparatus of the class described, the combination with at least one setting disk, teeth arranged on said disk, and means to rotate said disk, of a cam movable along said teeth and adapted to shift the same into and out of operative positions, a cam disk adapted to set said cam in operative position relatively to the teeth, and means to set the cam in inoperative position. 100

2. In an apparatus of the class described, the combination with at least one setting disk, teeth arranged on said disk, and means to rotate said disk, of a hand lever and a cam mounted thereon and adapted to be moved therewith along the teeth and to shift the same into and out of operative positions, a cam disk adapted to set said cam in operative position relatively to the teeth, and means to set the cam in inoperative position. 110

3. In an apparatus of the class described, the combination with at least one setting disk, teeth arranged on said disk, and means to rotate said disk, of a cam movable along said teeth and adapted to shift the same into and out of operative positions, a cam disk rotatably mounted coaxially of the disk and adapted to set said cam in operative position relatively to the teeth, and means to set the cam in inoperative position. 125

4. In an apparatus of the class described, the combination with a plurality of setting disks located coaxially one beside the other, teeth arranged on said setting disks, and means to rotate the setting disks, of cams one for each of the setting disks movable along the teeth and adapted to shift the same into and out of operative positions, cam disks one for each of the cams adapted to 5 means to set the cams in operative positions relatively to the teeth, common operating means for all the cam disks, and means to set the cams in inoperative position.
5. In an apparatus of the class described, the combination with a plurality of setting disks located coaxially one beside the other, teeth arranged on said setting disks, and means to rotate the setting disks, of cams one for each of the setting disks movable along 10 the teeth and adapted to shift the same into and out of operative positions, cam disks one for each of the cams adapted to set the cams in operative positions relatively to the teeth, a rock shaft carrying a hand lever, arms on 15 said shaft, links connecting the arms with the cam disks, and means to set the cams in inoperative positions.
6. In an apparatus of the class described, a rotating setting disk having shiftable 20 teeth, means for shifting said teeth into and out of operative position, means for rotating said disk, and interlocking means between said teeth shifting means and said disk rotating means to prevent the operation of either of said means while one or 25 the other is out of initial position.
7. In an apparatus of the class described, a rotatable setting disk having a plurality of shiftable teeth, means for shifting said teeth into and out of operative position, means for rotating said disks, a notched disk 30 associated with the means for rotating the setting disks and adapted to be rotated when said means is operated, a second notched disk 35 associated with said tooth shifting means and rotated when said means is actuated, and a slide normally engaging the notch of 35
- said first-mentioned notched disk and adapted to be shifted into the notch of said second-mentioned disk when the setting disk 50 rotating means is operated and the tooth shifting means is in normal position.
8. In an apparatus of the class described, a rotatable setting disk having a plurality of shiftable teeth, means for shifting said teeth into and out of operative position, means for rotating said disks, a notched disk 55 associated with the means for rotating the setting disks and adapted to be rotated when said means is operated, a second notched disk 60 associated with said tooth shifting means and rotated when said means is actuated, and a slide normally engaging the notch of said first-mentioned notched disk and adapted to be shifted into the notch of said second-men- 65 tioned disk when the setting disk rotating means is operated and the tooth shifting means is in normal position, said slide being formed with notches arranged for interlocking engagement with said teeth shifting 70 means.
9. In an apparatus of the class described, numeral setting mechanism, a numeral registering mechanism, means for actuating said numeral setting mechanism to transmit a 75 numeral to said registering mechanism, and interlocking means between said numeral setting mechanism and said actuating means to prevent the operation of said numeral setting mechanism or said actuating mecha- 80 nism while one or the other is out of initial position, said interlocking means including a member engageable with said numeral setting means, and a slide formed with notches therein engageable by said member to lock 85 said numeral mechanism and said actuating means.

In testimony whereof I have hereunto set my hand in presence of two subscribing witnesses.
